UNITED STATES PATENT OFFICE

2,633,575

GIRDLE CONSTRUCTION

Flora R. Hickey, Miami, Fla.

Application June 15, 1950, Serial No. 168,299

1 Claim. (Cl. 2-39)

1 This invention relates to ladies' undergarments and, more particularly, to new and useful improvements in girdles.

Girdles are known which are adjustable to the configuration of the user and other nonadjustable girdles are known which are openable to facilitate donning the same. The non-adjustable girdles are, of course, limited in their use and thus often are unsatisfactory, and the known adjustable girdles are unsatisfactory in that the adjustment must be lost in order to remove the same from one's person. Thus the girdle must be adjusted each time it is donned.

One object of the invention is the provision of a girdle which is openable to facilitate donning and removing the same and which is adjustable to the particular configuration of the user, said adjustment not being lost each time the girdle is removed.

Another object of the invention is to construct and arrange the adjustment means so that the wearer's body surface is not pinched or otherwise discomfited thereby.

Still another object of the invention is to associate with said opening means, padding means to protect the body surface from uncomfortable contact with the said opening means.

For further comprehension of the invention, and of the objects and advantages thereof, reference will be had to the following description and accompanying drawings, and to the appended claim in which the various novel features of the invention are more particularly set forth.

In the accompanying drawings forming a material part of this disclosure:

Fig. 1 is a front view of the girdle.

Fig. 2 is a rear view of the girdle.

Fig. 3 is a side view of the girdle as seen from the right of Fig. 1.

Fig. 4 is a side view similar to Fig. 3 but illustrates the opening means in open condition.

Fig. 5 is a fragmentary view from the inside of the girdle and illustrates the protective means associated with the opening means.

Fig. 6 is a fragmentary enlarged view of the adjustment means.

Fig. 7 is a fragmentary sectional view on line 7-7 of Fig. 6.

Fig. 8 is a fragmentary sectional view on line 8-8 of Fig. 5.

The girdle, according to the present invention, includes a front portion consisting of a pair of vertical fabric panels 10 joined together at their center edges by stitching 11. To the outer edge of each panel 10 is secured an elastic gusset or inset 12 and an elastic gusset or inset 13, the

former being located at the upper edge of the garment and the latter at the lower edge. Also secured to the outer edge of each panel 10, between the elastic insets 12 and 13 is a fabric side panel 14, see also Fig. 3. The elastic gussets 13 are each in the form of a segment which is broadest at the lower edge of the garment, and the side panel 14 is secured to the arcuate side edge thereof by stitching 15. The upper edge of each side panel 14 is secured by stitching 16 to the lower edge of the appropriate elastic gusset 12.

As shown in Fig. 2, the rear of the garment also comprises a pair of vertical fabric panels 17 secured together at their center edges by stitching 18. The outer edge of each rear panel 17 is secured by stitching 20 to an upper edge elastic gusset 21, the side panel 14 and a lower edge gusset 22. The gussets 21 and 22 are substantially identical with the gussets 12 and 13 described above, the former being secured to the upper edge of the side panel by stitching 23 and the latter to the arcuate lower portion of the side panel by stitching 24.

It will be seen that the elastic gussets 12, 13, 21 and 22 will cause the garment to hug both the diaphragm and the hips or thighs of the wearer, so that the upper and lower edges of the garment present a smooth non-bulky appearance.

In order to provide for opening the garment to facilitate donning and removing the same, the means shown in Figs. 3, 4, 5 and 8 are provided. This means consists of a slit separating the gussets 12 and 21 at one side of the garment and extending downward in the associated side panel 14 about two-thirds of the distance to the lower edge thereof. To the inner face of each lip of said slit is secured the fabric tape of a zipper fastener 25 by which the slit can be opened or closed. In order to protect the zipper 25 from the expansive forces of the body of the garment's wearer, other means are provided for holding the lips of the slit in adjacent positions. One side of the slit has secured thereto inside of the zipper taping a length of fabric tape 26 to which are secured in vertically spaced relationship a plurality of eyes 27 for cooperation with hooks 28 secured on a tape 30 fixed to the other edge of the slit. With the hooks 28 and eyes 27 engaged the said slit is held in the appropriate position to be closed by the zipper 25 which is not placed under any lateral strains.

In order to protect the wearer of the garment from any discomfort due to the zipper 25 and the associated hooks and eyes, a padded member 31 is secured to the inner face of the garment on

one side of the slit and overlies all of the opening and closing means associated with said slit. Preferably the member 31 consists of a strip of velvet or other thick cushiony material.

In order to provide for adjusting the garment to the particular configuration of the wearer so as to provide maximum abdominal and diaphragm control the means illustrated in Figs. 2, 6 and 7 are provided.

The stitching 18 which joins together the adjacent edges of the rear panels 17 extends from the lower edges of said panels to approximately the vertical center thereof at which point the adjacent edges of the panels are set back to provide a vertical slot or cutout 32 which extends to the upper edge of the garment. Each panel 17 has secured to the inner face thereof adjacent the slot 32 a length of taping 33 which forms with a second tape 34 a pocket for a steel bone 35 which extends the length of said slot. Secured in place between each tape 34 and the associated panel 17 are a plurality of vertically spaced eyes 36 through which is laced, from bottom to top, a suitable ribbon 37. It will be seen that by lacing the ribbon 37 tightly the circumferential dimension of the garment will be lessened, and if the ribbon be loosely laced the said dimension will be increased. Once the proper adjustment of the ribbon has been made the same is knotted in any suitable manner to retain the adjustment.

It is to be noted that the bones 35 will prevent pinching or other discomfiture to the body of the wearer due to the eyes 36 and the ribbon 37.

Preferably a reinforcing member 39 is secured to the panels 17 at the lower edge of slot 32 to relieve some of the strain from the stitching 18.

The garment also is provided with steel or spiral bones 38 located as shown in Figs. 1, 2 and 7 to provide the desired shaping support for the garment.

While I have illustrated and described the pre-

ferred embodiment of my invention, it is to be understood that I do not limit myself to the precise construction herein disclosed and the right is reserved to all changes and modifications coming within the scope of the invention as defined in the appended claim.

Having thus described my invention, what I claim as new, and desire to secure by United States Letters Patent is:

In a girdle having a one-piece tubular body for encircling the torso of the human body, the rear of the tubular body having a first slit extending from the top edge thereof to a point at about the vertical center of the tubular body, horizontally aligned eyelets mounted on the material of the tubular body on opposite sides of said slit, a lace engaged through said eyelets to have its free ends tied together for sizing the top portion of the tubular body, the tubular body having a second slit spaced from said first slit and extending downward from the top edge of the girdle to a point below the bottom end of said first slit, and closure means secured to the material of the tubular body on opposite sides of said second slit, so constructed that the top portion of the tubular body can be opened and closed at said second slit without disturbing the adjustment of said lace at the rear of the tubular body.

FLORA R. HICKEY.
